UNITED STATES PATENT OFFICE.

HERBERT W. KENWAY, OF NEWTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EYELETING-MACHINE.

1,271,720.

Specification of Letters Patent.

Patented July 9, 1918.

Application filed September 1, 1914. Serial No. 859,632.

To all whom it may concern:

Be it known that I, HERBERT W. KENWAY, a citizen of the United States, residing at Newton, in the county of Middlesex and 5 State of Massachusetts, have invented certain Improvements in Eyeletting-Machines, of which the following description, in connection with the accompanying drawings, is a specification, like reference characters on 10 the drawings indicating like parts in the several figures.

This invention relates to improvements in machines for setting eyelets or similar fastening devices, and particularly to machines 15 for setting blind or invisible eyelets.

Heretofore in setting invisible eyelets it has been the practice to utilize an upsetting die which has been forced through the hole in the outer or leather part of the upper into 20 such position between the two parts that the end of an eyelet barrel inserted through the lining part is clenched upon the covered surface of the lining. This has necessitated a hole in the outer part of the upper at least 25 as large as the eyelet barrel and even a hole of such diameter has been more or less stretched and distorted by the forcing through it of the upsetting die which is necessarily of greater diameter than the eyelet 30 barrel. In boots and shoes of many styles it is desired to make in the outer part of the upper holes of diameter substantially less than the diameter of the eyelet barrel, but with the setting tools heretofore known this 35 has been impossible. An important object of the present invention is to provide an eyelet setting machine by which the difficulties above discussed may be avoided and which will permit the setting of blind or 40 invisible eyelets beneath a hole of smaller diameter than heretofore. This result is effected, in accordance with the embodiment 45 of the invention herein shown, by utilizing an expansible upsetting die which may be introduced through one part of the upper in a contracted condition in which its diameter is smaller than the inner diameter of the eyelet barrel, and then expanded sufficiently 50 to clench the eyelet barrel when the latter is forced against it.

The expansible upsetting die may be inserted either through the hole in the lining part or through the hole in the outer part

of the upper, but as herein shown it is arranged to be carried by the eyelet inserting 55 set and passed through the lining part from the same side that the eyelet is inserted. This construction is believed to be broadly novel regardless of how the upsetting die is inserted and while it is particularly advantageous 60 in connection with a machine for setting blind or invisible eyelets its use is not limited to this class of work but has a broader application. When the upsetting die is arranged to be carried by the eyelet 65 inserting set it may also have the function of the usual center spindle which picks the eyelet from the raceway and holds it in position during the inserting operation. Any desired means may be employed for ex- 70 panding the upsetting die after it has entered the work, but as herein shown the feeding tool is utilized for this function. Such arrangement constitutes another im- 75 portant feature of the invention and is ad- 80 vantageous in that it offers convenient and satisfactory mechanical means for expanding the upsetting die without introducing additional mechanism into the organization of the machine. As herein shown the feed- 85 ing tool is arranged to be inserted in a previously punched hole in the upper and to be retracted sufficiently to disengage the lining part when the upsetting die is brought into engagement with the feeding tool prior to the setting operation.

Still another feature of the invention relates to the construction of the upsetting die itself which, as herein shown, is comprised of a plurality of complementary sections 90 bound together at their lower ends and maintained normally in a contracted condition by their own resiliency. An important object of this construction is that the die may be assembled with no space between its 95 sections and consequently there will be only a slight and unobjectionable separation of the sections when the setting die is expanded.

Other features of the invention relate to a novel arrangement of the eyelet presenting 100 and upsetting dies wherein these are both initially located upon the same side of the part of the work in which the eyelet is to be set and the upsetting die is moved through only that portion of the work in 105 which the eyelet is to be set. In the illus-

trated construction, the punching and feeding tools are located on the opposite side of the work from the tools for inserting and clinching the eyelet.

5 These and other features of the invention will be best understood and appreciated from the following description of a preferred embodiment thereof selected for purposes of illustration and shown in the accompanying drawings in which,

10 Figure 1 is a view in perspective of so much of an eyeleting machine as is necessary to understand the present invention;

15 Fig. 2 is a view in perspective on an enlarged scale of the feeding and setting tools;

Fig. 3 is a view in front elevation, partly in section, of the parts shown in Fig. 1; and

20 Figs. 4 and 5 are sectional views showing the setting tools in different positions.

25 In the accompanying drawings the invention is illustrated as embodied in the well-known Universal eyeleting machine, but it will be apparent that any other eyeleting machine would do as well.

30 The machine frame 2 is provided with vertical journals for the plunger 4 which carries the eyelet inserting set 6 and the expansible upsetting die 8. A stationary work plate 10 is secured to the machine frame and is cut away to permit the passage of the setting and punching tools. The frame also carries a swinging head 12 in which is mounted an oscillating feeding lever 14. At one side of the lever 14 is a second lever 16 which carries a punch 18 arranged to coöperate with a punching die 20 disposed beneath it in a slot in the work table 10. A presser foot 22 of the usual construction is provided to hold the work stationary between the feeding 35 steps. The actuating mechanism for the various tools is not herein illustrated as it forms no part of the present invention and may well be of similar construction to the corresponding mechanism of the Universal 40 eyeleting machine.

45 The eyelet carrying set 6 is of the usual construction, being properly shaped at its upper end to fit the flange of the eyelets to be inserted. As shown in Fig. 3, it is ad-

50 justably retained in the upper end of the plunger 4. The expansible upsetting die 8 is mounted in a bore in the set 6 in place of the usual center spindle. It comprises three sections as shown in Fig. 2, each of 55 which forms 120° of its circumference. The sections are shouldered at their lower ends to fit upon the upper end of a pin 24 and are bound together and to the pin by a band 26. At its lower end the pin 24 rests upon 60 a compression spring 25 contained in a recess in the plunger 4. In making the upsetting die its parts are firmly bound in place and then brazed or sweated together. The sections of the upsetting die are of resilient 65 nature and are so shaped as to be normally

in contact with each other so that the die as a whole is in a contracted condition.

70 The upper end of the upsetting die 8 is flat and of a diameter slightly less than the inner diameter of the eyelets to be set. Immediately beneath its upper end the upsetting die is reduced in diameter, its surface being curved so as to form an upsetting surface 28 facing toward the eyelet inserting set 6. The inner corner of each section is 75 beveled off so that a central depression 30 is formed in the upper surface. As shown in Fig. 3 the upsetting die 8 is arranged to be passed through the hole in the lining part 50 of the upper in its normal or contracted 80 condition and in this condition the diameter of its upper end is slightly less than the diameter of the hole in the work.

85 The feeding tool 32 is mounted in the forward end of the lever 14 and provided at its lower end with a conical expanding projection 34 shaped to enter the depression 30 in the upsetting die and expand the sections thereof. The plunger 32 is secured to the lower end of a stem 36 which extends upwardly through the lever 14 where it is provided with a pair of adjustable set-nuts 40 by which the initial position of the tool in the leather may be regulated. The lever 14 is chambered at its lower end to receive the 90 plunger 32 and is counter-bored above the chamber to receive a compression spring 38 arranged to bear upon the upper end of the plunger and hold it in its lower or normal position. In its normal position the upper 95 end of the plunger 32 stands below the seat of its chamber by a distance equal substantially to the thickness of the material in which the eyelet is set and when it is engaged by the upsetting die as shown in Fig. 3 it 100 is forced upwardly until its seat is encountered and thus retracted from the lowermost layer or layers of material. After the upward movement of the plunger 32 is arrested, however, the continued upward 105 movement of the upsetting die 8 forces the upper ends of its resilient sections against the conical projection 34 and so effects the expansion of the die as a whole.

110 The operative or retracted position of the die expanding plunger 32 is positively determined by its engagement with the annular shoulder forming its seat. The upsetting die in its upward movement is advanced by the compression spring 25 which 115 consequently serves to limit the pressure exerted between the upsetting die and the die expanding plunger 32. This arrangement is of importance in view of the delicate construction of the upsetting die which renders 120 it likely to be broken if subjected to a pressure of more than a moderate amount.

125 In operating the machine herein described the work is placed upon the table 10 with the point at which the first eyelet is to be 130

set in alinement with the punch 18, and the machine is then set in operation. The punch immediately descends and perforates the work, being then elevated and moved 5 toward the right to an inoperative position. The forward end of the lever 14 is then moved toward the right and downwardly to insert the feeding tool 32 in the previously punched hole. The feeding operation is 10 then effected by swinging the lever 14 toward the left whereupon the hole in the work is moved into alinement with the path of the setting tool. The plunger 4 is then elevated and the end of the upsetting die 8 passes into the hole in the work forcing the 15 feeding tool 32 upwardly out of the lining part 50 and then being expanded as shown in Fig. 4 and brought to rest with its upsetting surface just beneath the uppermost part 20 of the work. The continued upward movement of the plunger 4 elevates the eyelet inserting set 6 which carries the eyelet upwardly upon the upsetting die 8, inserting its barrel through the part 50 of the work 25 and forcing it against the upsetting surface 28 by which it is clenched upon the covered surface of the lining. The plunger 4 then moves downwardly and simultaneously the lever 14 is elevated moving the expanding 30 projection 34 upwardly and thus permitting the sections of the upsetting die to resume their normal contracted position. This condition is illustrated in Fig. 5 from which it will be seen that the upsetting die may now 35 be lowered and withdrawn from the work through the barrel of the clenched eyelet.

While the present invention has been described in connection with the operation of inserting blind or invisible eyelets, it possesses many novel structural features which may have useful application in machines for setting eyelets or other tubular fasteners in the regular manner or in work of various different kinds.

Having thus described my invention, what I claim as new and desire to secure by Letters Patent of the United States is:—

1. In an eyeletting machine, an expandible upsetting die, and a coöperating eyelet carrying set movable to present an eyelet to said die after the die has been expanded.

2. In an eyeletting machine, an expandible upsetting die, and means for expanding the die prior to the setting operation, said die being constructed and arranged to be automatically returned to its contracted condition when released from the action of the expanding means, without regard to the action of gravity.

3. In an eyeletting machine, an expandible upsetting die, and means for completely expanding the die after it has been passed into a hole in the work and prior to the setting operation.

4. In an eyeletting machine, an expandible

upsetting die comprising a plurality of resili- 70 ent sections, constructed and arranged so that their resiliency tends to maintain the operative portions in contracted position.

5. In an eyeletting machine, an expandible upsetting die comprising a plurality of relatively movable sections constructed and arranged to be normally self-contracting without regard to the action of gravity, and means for positively separating the sections. 75

6. In an eyeletting machine, an eyelet inserting set mounted for reciprocation, and an expandible upsetting die carried thereby.

7. In an eyeletting machine, an eyelet inserting set mounted for reciprocation toward 80 one side of the work, and an upsetting die initially located on the same side of that portion of the work in which the eyelet is to be set.

8. In an eyeletting machine, a frame, a work support mounted thereon, and an eyelet inserting set and an upsetting die mounted for movement with relation to the work support, said set and die being relatively movable in a direction longitudinally 90 of the eyelet to be set and being both initially located on the same side of that portion of the work in which the eyelet is to be set as the support.

9. In an eyeletting machine, an expandible 95 upsetting die, and a combined work feeding and die expanding member.

10. In an eyeletting machine, a punch, a feed member arranged to enter the punched hole, and an expandible upsetting die arranged to be expanded by the feeding member. 100

11. In an eyeletting machine, means located on one side of the work for punching and feeding the same, and means located initially on 105 the other side of that portion of the work in which the eyelet is to be set constructed and arranged for both inserting and clenching an eyelet.

12. In an eyeletting machine, an eyelet inserting set, and an upsetting die initially located on one side of that portion of the work in which the eyelet is to be set and movable to the other side of said portion of the work prior to the setting operation and in timed 115 relation to the set.

13. In an eyeletting machine, eyelet setting tools mounted for relative movement in timed relation, one of said tools being movable in a predetermined path from one side 120 to the other of that portion of the work in which the eyelet is to be set.

14. In an eyeletting machine, eyelet setting tools mounted for relative movement in timed relation, one of said tools being movable in a fixed path through that portion of the work in which the eyelet is to be set, and the other of said tools being thereupon moved to effect the clenching operation. 125

15. In an eyeletting machine, eyelet setting 130

- tools, and mechanism for effecting relative movement of said tools organized to move one of said tools previously to the insertion of the eyelet to be set through only that portion of the work in which the eyelet is to be set.
16. In an eyeletting machine, a work support, eyelet setting tools including an expandable upsetting die movable through a portion of the work upon the support in an unexpanded condition and being arranged for expansion after it has passed through the work.
17. In an eyeletting machine, a work feeding member constructed and arranged to be inserted in the work preparatory to the feeding operation, and means for moving the tool to withdraw it partially but not wholly from the work at the conclusion of the feeding operation and prior to the setting operation.
18. In an eyeletting machine, eyelet setting tools, and a feeding member constructed and arranged for a limited retractive movement in response to pressure of one of the setting tools.
19. In an eyeletting machine, an expandable die, means for expanding the die, and means for limiting the pressure between the die and the die-expanding member.
20. In an eyeletting machine, a punch for perforating both the outer and lining parts of an upper, a feeding tool for entering the hole so formed by said punch, an expandable upsetting die movable through the lining part and arranged to retract the feeding tool, and an eyelet inserting set.
21. In an eyeletting machine, an eyelet inserting die having a spindle centrally located and shaped at its end to constitute an upsetting die.
22. In an eyeletting machine, an eyelet inserting die, an upsetting die movable therewith, means for moving the eyelet inserting die toward the work to enter the upsetting die therein, and means for arresting the movement of the upsetting die in the work while the movement of the inserting die continues.
23. In an eyeletting machine, a frame, a plunger mounted in bearings in said frame for reciprocation in a predetermined path with respect to the machine, an eyelet inserting die carried by said plunger and arranged to insert an eyelet in the work, and an upsetting die also carried by said plunger and arranged to coöperate with the inserting die to upset an eyelet inserted in the work.
24. In an eyeletting machine, a reciprocating plunger, relatively movable inserting and upsetting dies carried thereby, and means for arresting the movement of one of the dies before the other.
25. In an eyeletting machine, an expandable die, a die-expanding member, a movable carrier for said member, and means for adjusting the normal position of said member in the carrier.
26. In an eyeletting machine, an eyelet raceway, an eyelet inserting set, and an expandable spindle carried thereby arranged to thread an eyelet in the raceway and deliver it to the inserting set, said spindle having formed upon its end a concave annular upsetting surface disposed away from the end of the spindle.
27. An eyeletting machine, having, in combination, an eyelet inserting set, a raceway for supplying eyelets, and a tool constructed and arranged first to pick an eyelet from the raceway and then clench the end of the eyelet barrel.
28. A machine for setting invisible eyelets, having, in combination, a punch for perforating the outer and lining portions of an upper, an expandable upsetting die arranged to be inserted through the hole in one portion of the upper and then expanded, and a set for forcing an eyelet against the expanded die.
29. A machine for setting invisible eyelets, having, in combination, a punch, an expandable upsetting die arranged to be inserted through one of two parts of an upper perforated by the punch, and a die expanding member mounted independently of the expandable die.
30. In an eyeletting machine, an expandable upsetting die, said die being normally contracted so as to be passed through a hole in one layer of the work which is smaller than the ultimate size of the upsetting surface of the expanded die, and means for passing an eyelet through one layer of the work and forcibly presenting the same against the upsetting surface of said die to thereby upset it upon a part of the layers of the work.
31. In an eyeletting machine, an expandable upsetting die arranged to be interposed between the layers of the work and then expanded to provide an enlarged upsetting surface, and means for presenting an eyelet through a portion of the layers of the work against the upsetting die when it is in expanded condition.
